Design N° 767

William T. Coggeshall's Design for a Fire Place.

Patented Feb. 19th 1856.

William T. Boggsall of Fall River, Mass.
Letters Patent No. 767 Dated Feb. 14, 1856.

~~~~~
The Schedule referred to in these Letters Patent and making part of the same.
~~~~~

To all persons to whom these Presents shall come.

Be it known, that I, William T. Boggsall of Fall River in the county of Bristol and State of Massachusetts, have invented or produced a new and ornamental design for a Parlor Fire Place or Stove, which I do hereby declare is fully exhibited in the accompanying drawings, of which

water urn, the top plate, the top and front plates and the blower.

Figure 3, is a vertical section taken through the right side plate and the right half of the urn and top plate.

My design is not intended to include the title "Vesta Parlor Stove No. 2," as shown in bas relief on the main hearth plate.

In the drawings A is a water urn supported on an elongated cover plate C.

B, is the top plate.

D, the front plate.

E, the cover plate of the ash pit.

F, the front plate of the ash pit.

G, the main hearth plate.

H, the side plate.

I.K. doors.

E.D.S. 767

M. the blower.

The ornamental design or character of each of the above members or parts of which enters into the design I have produced, is duly shown in the drawings, with clearness sufficient to enable a pattern maker of ordinary skill in the art of carving to perfectly comprehend and produce the same.

I therefore claim as of my invention or production, the ornamental design of the various parts of the stove or fire place as above referred to and represented in the drawings herein mentioned.
